PUNCH AND SHEARING MACHINE

Marcellin L. Grappe, Columbia Heights, Fair
Lawn, N. J.

Application January 11, 1938, Serial No. 184,475

7 Claims. (Cl. 164—86)

The invention relates to a punch and shearing machine and more especially to a combined hand or power operated punching and shearing machine.

5 The primary object of the invention is the provision of a machine of this character, wherein a plurality of punches can be selectively actuated for punching operation and also varying shapes of metal material can be sheared or cut in a single operation of the machine.

Another object of the invention is the provision of a machine of this character, wherein the construction thereof is novel so that it is possessed of the universal activity in that sheet metal can be sheared or cut as may be required and also pieces of work punched, the machine embodying a plurality or clusters of punches of different sizes, these being selective for operation.

10 A further object of the invention is the provision of a machine of this character, wherein the punches on selectivity thereof as to size and form will be automatically or mechanically actuated for punching operation, being racked and tensioned for normally holding the same in inactive position in a novel manner.

15 A still further object of the invention is the provision of a machine of this character, which is simple in its construction, thoroughly reliable and efficient in operation, of vertical type, susceptible of turning movement for changing its position for operation, readily and easily operated and inexpensive to manufacture and install.

With these and other objects in view, the invention consists in the features of construction, combination and arrangement of parts as will be hereinafter more fully described, illustrated in the accompanying drawings, which disclose the preferred embodiment of the invention and pointed out in the claims hereunto appended.

In the accompanying drawings:

Figure 1 is an elevation of the machine constructed in accordance with the invention looking toward the front thereof.

Figure 2 is a top plan view.

Figure 3 is an end elevation.

Figure 4 is an opposite end elevation partly in section.

Figure 5 is a fragmentary enlarged sectional view taken on the line 5—5 of Figure 4 looking in the direction of the arrows.

Figure 6 is a fragmentary sectional view taken on the line 6—6 of Figure 5 looking in the direction of the arrows.

Figure 7 is a rear elevation of the machine.

Figure 8 is a detail perspective view of a spacer piece for the punch rack.

Figure 9 is a perspective view of one of the punches.

Figure 10 is a fragmentary enlarged horizontal sectional view taken through a series of punches and the rack therefor approximately on the line 10—10 of Figure 6 and looking in the direction of the arrows.

Similar reference characters indicate corresponding parts throughout the several views in the drawings.

Referring to the drawings in detail, the machine constituting the present invention comprises a stand 10 having downwardly divergent supporting legs 11 in association with horizontal rungs 12 and this stand has built therewith a horizontally disposed top 13 on which is bolted or otherwise fastened a bed 14 of circular form for a turntable 15 being rotatably arbored or pivoted at 16 and constitutes the base for the frame 17 which is of substantially C-shape described in detail hereinafter.

The frame 17 has a horizontally disposed work bed 18 and this frame opens in the direction of the front of the machine. The frame 17 has formed therewith at the upper portion of the same and in overhanging relation to the bed 18 a vertically disposed flat plate-like head 19 carrying spaced bearings 20 in which is journaled a horizontal shaft 21 provided with a longitudinally directed keyway 22. Below the shaft 21 is a horizontally disposed punch rack 23, being bracketed at 24 to the head 19. Within the rack 23 is a cluster of vertically slidable punch carriers 25 in the form of a plurality of plungers and having separably fitted therewith the punches 26 which are of different sizes with respect to each other and coact with a stationary perforated anvil or die 27 horizontally fixed on the bed 18 beneath the punches 26 and upon which rests the work to be punched, the perforations 28 therein being for accommodating the punches 26 on actuation of the plungers 25 carrying the same.

The carriers in the form of the plungers 25 are separated from each other by spacer pieces 29 interposed therebetween and held within the rack 23, these pieces being windowed at 30 to effect clearances for coiled compression springs 31 which are received in recesses 32 forming pockets therefor in adjacent plungers 25 and function to normally hold the punches elevated in the rack 23 and under tension when articulated in the down stroke thereof.

Slidably carried on the shaft 21 is an actuator 35

eccentric or cam 33, being keyed at 34 in the keyway 22 in said shaft and this eccentric or cam can be manually moved to bring the same directly over a selected plunger 25 for operating its punch 5 26 carried thereby. The ring 35 is mounted on and secured on the cam or eccentric by a key 34 and includes an annular flanged groove 35' to slidably receive a tenon-shaped portion of a block 36. The latter has a dove tail groove 37 to receive any one of the tenons 38 on the plungers 10 25 and in this manner the block is detachably coupled selectively with any one of the plungers 25 and on rotation of the shaft 21 the eccentric or cam 33 will actuate a plunger 25 for punch- 15 ating operation by its companion punch 26 cooper- ating with the die or anvil 27.

The shaft, for example, is operated by a turning lever 39 although it may be power driven or otherwise mechanically or electrically operated.

20 Arranged at the rear of the head 19 is a rocking arm 40 turnable on the axle stud 41 projected from the said head and at one end is formed a toothed sector 42 meshing with a segmental gear 43 fixed to the lever 39 so that on reciprocation 25 or arcuate swing of the latter the arm 40 will rock. This arm 40 at the other end has a depending extension 44 carrying a movable shearing blade 45 coacting with a stationary blade 46 on the head 19 and in this manner work can be 30 sheared in the cutting of sheet metal or other material. The arm 40 is limited in its rocking movement by stop lugs 47 on the head 19 and accommodated within arcuate slots 48 provided in the arm 40.

35 Provided in the head 19 and in the arm 40 are registering shearing openings 49 and 50, respectively, these being of different shapes throughout the companion relation thereof so that a round bar, a square bar, an L bar or a T bar or other work can be severed or sheared when passed 40 through these openings 49 and 50 when registering with each other on the movement of the arm 40, the machine being universal in kind for punching and shearing uses.

45 The turntable 15 allows the frame 17 to be turned and in this way satisfying the requirements of an operator with respect to a selected positioning of the machine for the operation of the same.

50 The open front of the frame 17 enables an operator of the machine to easily select a punch 26 of meeting requirements and this is carried forth by the shifting of the cam or eccentric 33 to the location of the selected punch for the 55 working thereof on the turning of the shaft 22 by the lever 39 or otherwise.

The cam or eccentric 33 is of a kind to effect the proper throw of the plunger 25 for the successful working of its companion punch 26 carried

60 thereby.

It is to be understood that in the shearing operation flat, T-shaped, round, angle and square pieces of work of metal can be readily and easily sheared while metal work can be punched in 65 conformity with the requirements as to the size of the hole to be made or punched therein.

What is claimed is:

1. A machine of the character described comprising a frame having a bed, an upstanding head 70 on said frame above the bed, a plunger rack above said bed, spring tensioned plungers working within the rack, punches carried by said plungers, a shaft rotatably mounted on said head above the plungers, an actuating eccentric slidably keyed to 75 said shaft, a coupling block selectively engage-

able with the plungers and actuated by the eccentric for imparting stroking action to the said plungers, means for imparting movement to the shaft, spacer pieces in the rack between the plungers, and springs arranged in clearances in 5 said spacer pieces and housed in adjacent plungers for tensioning action thereon.

2. A machine of the character described comprising a frame having a bed, an upstanding head 10 on said frame above the bed, a plunger rack above said bed, spring tensioned plungers working within the rack, punches carried by said plungers, a shaft rotatably mounted on said head above the plungers, an actuating eccentric slidably keyed to 15 said shaft, a coupling block selectively engageable with the plungers and actuated by the eccentric for imparting stroking action to the said plungers, means for imparting movement to the shaft, spacer pieces in the rack between the plungers, springs arranged in clearances in 20 said spacer pieces and housed in adjacent plungers for tensioning action thereon, a rocking arm pivoted to said head, a stationary shearing blade on the frame, and a companion shearing blade 25 on said arm.

3. A machine of the character described comprising a frame having a bed, an upstanding head 30 on said frame above the bed, a plunger rack above said bed, spring tensioned plungers working within the rack, punches carried by said plungers, a shaft rotatably mounted on said head above the plungers, an actuating eccentric slidably keyed to 35 said shaft, a coupling block selectively engageable with the plungers and actuated by the eccentric for imparting stroking action to the said plungers, means for imparting movement to the shaft, spacer pieces in the rack between the plungers, springs arranged in clearances in 40 said spacer pieces and housed in adjacent plungers for tensioning action thereon, a rocking arm pivoted to said head, a stationary shearing blade on the frame, a companion shearing blade on said arm, and connections between the arm and said shaft for actuation of the arm on rotation of the 45 shaft.

4. A machine of the character described comprising a frame having a bed, an upstanding head 50 on said frame above the bed, a plunger rack above said bed, spring tensioned plungers working within the rack, punches carried by said plungers, a shaft rotatably mounted on said head above the plungers, an actuating eccentric slidably keyed to 55 said shaft, a coupling block selectively engageable with the plungers and actuated by the eccentric for imparting stroking action to the said plungers, means for imparting movement to the shaft, spacer pieces in the rack between the plungers, springs arranged in clearances in 60 said spacer pieces and housed in adjacent plungers for tensioning action thereon, a rocking arm pivoted to said head, a stationary shearing blade on the frame, a companion shearing blade on said arm, connections between the arm and said shaft for 65 actuation of the arm on rotation of the shaft, and a turntable supporting the frame.

5. A machine of the character described comprising a frame having a bed, an upstanding head 70 on said frame above the bed, a plunger rack above said bed, spring tensioned plungers working within the rack, punches carried by said plungers, a shaft rotatably mounted on said head above the plungers, an actuating eccentric slidably keyed to 75 said shaft, a coupling block selectively engageable with the plungers and actuated by the eccentric for imparting stroking action to the said

plungers, means for imparting movement to the shaft, spacer pieces in the rack between the plungers, springs arranged in clearances in said spacer pieces and housed in adjacent plungers for tensioning action thereon, a rocking arm pivoted to said head, a stationary shearing blade on the frame, a companion shearing blade on said arm, connections between the arm and said shaft for actuation of the arm on rotation of the shaft, a turntable supporting the frame, and a support for the turntable.

6. A machine of the character described comprising a frame having a bed, an upstanding head on said frame above the bed, a plunger rack above said bed, spring tensioned plungers working with in the rack, punches carried by said plungers, a shaft rotatably mounted on said head above the plungers, an actuating eccentric slidably keyed to said shaft, a coupling block selectively engageable with the plungers and actuated by the eccentric for imparting stroking action to the said plungers, means for imparting movement to the shaft, 15 spacer pieces in the rack between the plungers, springs arranged in clearances in said spacer pieces and housed in adjacent plungers for tensioning action thereon, a rocking arm pivoted to said head, a stationary shearing blade on the 20 frame, a companion shearing blade on said arm, connections between the arm and said shaft for actuation of the arm on rotation of the shaft, a turntable supporting the frame, and a support for the turntable.

10 25

actuation of the arm on rotation of the shaft, a turntable supporting the frame, a support for the turntable, and a stationary die on the bed for coaction with the punches.

7. A machine of the character described comprising a frame having a bed, an upstanding head on said frame above the bed, a plunger rack above said bed, spring tensioned plungers working with in the rack, punches carried by said plungers, a shaft rotatably mounted on said head above the 10 plungers, an actuating eccentric slidably keyed to said shaft, a coupling block selectively engageable with the plungers and actuated by the eccentric for imparting stroking action to the said plungers, means for imparting movement to the shaft, 15 spacer pieces in the rack between the plungers, springs arranged in clearances in said spacer pieces and housed in adjacent plungers for tensioning action thereon, a rocking arm pivoted to said head, a stationary shearing blade on the 20 frame, a companion shearing blade on said arm, connections between the arm and said shaft for actuation of the arm on rotation of the shaft, a turntable supporting the frame, a support for the turntable, and a stationary die on the bed for 25 coaction with the punches, the said arm and head being provided with companion shearing openings for accommodating varying shaped work.

MARCELLIN L. GRAPPE.
